MERCURY SWITCH RELAY

Carl H. Larson, Elkhart, Ind., assignor to The
Adlake Company, a corporation of Illinois

Application March 7, 1938, Serial No. 194,273

24 Claims. (Cl. 200—97)

This invention relates broadly to mercury switches, for certain features or parts of it can be used to advantage with almost any type of mercury switch. But more specifically, the invention pertains to that type of mercury switch in which spaced electrodes, together with a quantity of mercury and a magnetically responsive displacer are hermetically sealed within a glass envelope, after which the switch is associated with a coil which controls the movement of the displacer within the envelope to change the mercury level and thereby cause the electrical circuit between the spaced electrodes to be closed or opened according to the particular construction of the switch.

In general, the objects of the invention are to improve the mechanical strength of relays of this type, and particularly the electrode and time delay structure; to protect vulnerable parts of the relay from breakage due to blows, or if broken to confine the mercury within a jacket tightly fitted over the envelope so that adjacent property will not be damaged by mercury leaking out; to simplify manufacturing practices; to provide a switch structure which can meet rigid and difficult specifications for performance; and to provide means for obtaining uniform time delays, special contact opening and closing conditions, specified time delays even when the relay is quickly recycled, and a quick and positive resetting of the time delay element for each cycle of operation.

These objects and advantages, as well as others, will be elucidated in the description which follows, particularly when read in conjunction with the accompanying drawings, in which

Fig. 1 is a perspective view showing a preferred mounting for the relay;

Fig. 2 is a vertical, sectional view taken along the line 2—2 of Fig. 1;

Fig. 3 is a bottom plan view of the mounting with a portion of the bottom cover broken away to expose the interior of the base;

Fig. 3a is a fragmentary, perspective view of the switch base retaining sleeve;

Fig. 4 is a vertical, sectional view taken on the line 4—4 of Fig. 2, the switch itself, however, being shown in elevation;

Fig. 5 is an enlarged vertical, sectional view taken through a front contact switch embodying certain features of this invention, the switch being shown in its normal de-energized position;

Fig. 6 is a view corresponding to Fig. 5, the switch parts, however, being shown in the posi-

tion which they take immediately after the relay coil has been energized, but before the time delay element in the switch has permitted the spaced electrodes to be bridged with mercury;

Fig. 7 is a fragmentary, sectional view through the time delay thimble looking down upon the intermittently immersed electrode, the section line being indicated at 7—7 in Fig. 6;

Fig. 8 is a horizontal, sectional view taken on the line 8—8 of Fig. 6;

Fig. 9 is an enlarged, vertical, sectional view taken through a back contact switch which incorporates a modification of the time delay element shown in Fig. 5, the time delay element in this switch being adapted to effect a quick make and slow break of the electrical circuit through the spaced electrodes in the switch. The switch parts are shown in this figure in the position which they take substantially instantaneously after the associated relay coil has been de-energized and the displacer has dropped to the floor of the switch envelope.

Fig. 10 is a view corresponding to Fig. 9, but showing the relationship of the mercury fill to the time delay element and associated electrodes immediately after the displacer has been raised by the relay coil;

Fig. 11 is a view looking down upon the top of the time delay element;

Fig. 12 is a fragmentary, vertical section through the time delay element; and

Figs. 13 and 14 are views corresponding to Figs. 11 and 12, respectively, but showing a modified form of the time delay element.

The relay chosen to illustrate a preferred embodiment of the invention comprises a mercury switch generally designated 28, operatively associated with a coil 21 and mounted within a housing 22 which not only facilitates the mounting of the relay as a whole, but also provides the necessary mechanical protection for the switch from accidental blows.

The switch mounting

The upper portion of the housing 22 serves as the iron circuit for the coil 21 and it comprises a cylinder 23 of seamless, soft, cold-drawn steel tubing fitted at both ends with soft cold-rolled steel annuli 24 in the center openings of which top and bottom pole sleeves 25 and 26, respectively, are drive fitted leaving an air gap 27 between their inner ends. The top of the housing is covered by a cap 28 held in place by screws 29, and a terminal box 30 is then attached to the lower face of the iron circuit by means of screws 35

31. The terminal box is preferably an aluminum casting having an inturned flange 32 at the top through which the screws 31 pass. The rear and bottom of the casting are left open, the former being closed by a Bakelite plate 33 formed with an integral X-shaped projection having horizontal webs 34 and vertical webs 35 which form insulating barriers between half hard nickel silver terminal prongs 36 and 37 which are mounted on the plate 33 and are connected to the switch terminals and coil terminals, respectively. The plate 33 is held in place by screws 38 which enter enlargements or bosses 39 in the base casting. A cover plate 40 closes the bottom of the base casting and is held in place by screws 41.
32. The lower portion of the switch 20 is fitted with a Bakelite sleeve 42 which projects below the bottom of the switch envelope and is filled with sealing wax, as indicated at 43. When assembling the switch 20 with the coil 21, the cover 40 is removed and the switch inserted from the bottom until the base sleeve 42 of the switch strikes the lower margin of the bottom pole sleeve 26. A wire clip 44 is then sprung into place within slots formed in a metal sleeve 45 which is soldered or otherwise secured to the outer periphery of the downwardly projecting portion of the lower pole sleeve 26. The clip has a head 46 which fits within an opening 47 in the sleeve and the two ends of the clip when pressed together enter a bayonet slot 48 on the other side of the sleeve where they are retained by shoulders 49 when pressure on the free ends of the clip is released. Preferably the clip 44 is made of music wire, or other suitable resilient material. Notches 50 are formed in the lower margin of the sleeve 45 to accommodate the lead wires from the switch.
33. The relay as a whole is adapted to be mounted on a wall by means of a bracket 51 of cold rolled steel which is rigidly attached to the coil cylinder 23, and a special plug (not shown) is used to receive the relay terminals and the X shaped insulating barrier associated with the plate 33. The housing furnishes full protection to the switch 20 from accidental blows.

Switch having delayed make

34. The switch shown in Figs. 5-8 inclusive is of the type which has a delayed make, i. e. a certain time interval elapses between the time that the relay coil changes its state of energization or deenergization and the time when the electrical circuit through the switch electrodes is closed. The switch may be either of the front contact type or the back contact type, the one shown in the drawings being a front contact switch inasmuch as energization of the coil 21 lowers the displacer and tends to close the circuit between the electrodes of the switch.

35. The switch comprises a switch envelope 55 through the base of which spaced electrodes 56 and 57 are sealed. Both of the electrodes are covered for at least a portion of their length by glass insulating sleeves 58, the one associated with the electrode 56 being formed in two sections which are separated by a space indicated at 59, leaving a portion of the electrode bare, and the one associated with the electrode 57 terminating just below the end of that electrode, leaving an exposed end or contact 60. The upper end of the insulating sleeve is flared out, as indicated at 61, to form a seat for a ceramic cup 62, and when the materials for the cup 62 and

sleeve 58 are properly selected, the two may be fused together to form a firm bond.

36. A time delay element, generally designated 63 is supported by at least one and preferably both of the electrodes, and it comprises a glass thimble or bulb 64 having its lower portion fused, as indicated at 65, to the upper end of the electrode 56 and the adjacent portion of the electrode 57 in such a manner that the electrode 56 is embedded within the glass and the continuity 10 of the insulating sleeve 58 surrounding the electrode 57 is preserved.

37. The thimble 64 has a relatively large opening 66 in one of its side walls, the area of this opening preferably being at least as great as the cross 15 sectional area of the thimble. A smaller opening 67 in the upper portion of the thimble receives a porous plug 68 of suitable ceramic material, and again when proper materials are used, the porous block may be sealed into place by 20 fusion with the enveloping glass wall 69 of the thimble 64.

38. The switch contains a mercury fill 70, a magnetically responsive displacer generally designated 71 consisting of an iron sleeve 72, an inner 25 glass sleeve 73, guide washers 74 and top and bottom springs 75 and 76, respectively, the latter being tightly telescoped over the projecting ends of the inner glass sleeve 73 to hold the iron sleeve 72, and guide washers 74 in proper relationship to the glass sleeve 73.

39. The switch contains a gas fill preferably including helium and hydrogen, and after the switch parts have all been assembled in the switch blank (which includes the tube 55 through the base of which electrodes 56 and 57 with their associated insulating sleeve and superposed thimble are sealed) and the gas fill inserted, the upper end of the envelope is sealed 40 off, as indicated at 77 to hermetically seal the switch parts within the envelope.

40. The air gap 27 between the pole sleeves 25 and 26 is so positioned with reference to the displacer 71 that when the coil 21 is energized, the displacer is drawn downwardly by magnetic force to the position in which it is shown in Fig. 6 and the immediate result of this movement is that mercury is displaced from the low level shown in Fig. 5 to the level in which the mercury is shown in Fig. 6. The gas trapped within the thimble 64 restrains the movement of mercury within the thimble to circuit closing position and the time that it takes the mercury within the thimble 64 to reach the edge 78 of 55 the cup 62 after energization of the coil 21 is the time delay interval of the switch in its delayed circuit closing action.

41. As the mercury within the thimble 64 gradually rises due to the escape of gas through the 60 porous plug 68, (the difference between the outside mercury level and the level of mercury within the thimble creates a head which forces gas from the thimble through the plug 68), it will finally reach a position of equilibrium indicated 65 by the line 79, in which there will be a common mercury level on the inside and on the outside of the time delay thimble 64. If now the coil is deenergized, the displacer 71 will rise by its buoyancy to the position in which it is shown in 70 Fig. 5 and the mercury level on the outside of the thimble 64 will immediately fall below the top of the opening 66 with the result that the mercury within the thimble will substantially instantaneously fall from the thimble and away 7.

from the contact 60 to break the circuit through the electrodes 56 and 57.

The switch which has been described has certain inherent advantages over earlier types of switches, and these will be briefly mentioned:

(a) The method of attaching the time delay element 63 to the insulating sleeve surrounding one of the electrodes (or both) constitutes a convenient method of fabrication and at the same time gives great stability to the electrode structure. It is far superior in mechanical strength to the method of attachment shown in my earlier Patent No. 1,967,946, and the desired time delay characteristic of the switch can be much more easily obtained and maintained than was heretofore possible. The rigidity which is furnished by supporting the time delay element by both of the spaced electrodes contributes its share to the perfection of the switch as a whole.

(b) It will be noticed that the intermittently immersed contact 60 is at one side of the thimble 64 and that the opening 66 is on the other side. The purpose of this arrangement is so that the mercury can fall away from the contact 60 with as little restraint as possible because in some electrical circuits, the breaking of the electrical circuit controlled by the switch must be within a very few thousandths of a second after the coil has been de-energized. It is for this reason that the opening 66 is made equal to or greater than the cross sectional area of the thimble. It has also been found by experimentation that the time required for the mercury to drop away from the electrode 60 was substantially less when a side opening, such as the opening 66 is used instead of the body opening shown in my prior Patent No. 1,967,946.

(c) The slight pitch given to one edge of the refractory cup 62 insures that gas will not be trapped within the cup since the mercury will flow in from the low side of the cup and gas will flow out of the high side.

(d) The time delay element 63 can be given any desired time delay characteristic by proper selection for the material of the plug 68. Preferably the plug is made of a product known as Alundum, and grades RA 98, RA 360 and RA 84, for short, medium and long time delays, respectively, have been found satisfactory, particularly since this type of ceramic material will fuse readily with the particular type of glass that is used in the switch, namely 733 A.

(e) It should be noticed that the displacer 71 when in the position it takes upon energization of the coil 21, has its lower spring 76 resting on the floor of the switch envelope and the parts of the switch are proportioned so that the displacer will occupy this position when the coil is energized. The result is that the outside mercury level will always rise the same distance above the top of the opening 66 so that the gas pressure differential between the inside and outside of the thimble, due to the head of mercury, will be the same for all operations of the switch. Uniformity of results is thereby assured unless, of course, the voltage on the coil is lower than that for which the relay was designed. However, since the displacer is completely submerged in the mercury fill, variations in the voltage of the coil will have little or no effect on the uniformity of switch operation.

(f) It sometimes happens that when the relay coil is operating on an alternating current voltage which is lower than that specified for the relay, the displacer will have a certain amount of re-

ciprocating movement due to voltage changes which necessarily affect the outside mercury level and would cause false makes or breaks in the circuit in the event that the time delay element were carried by the displacer. In the switch shown, however, these oscillations of the displacer have no perceptible effect on the inside mercury level, and the switch, therefore, functions according to specification under these adverse conditions.

(g) The mercury cup 62 is formed so that it not only is assured of being filled on each operation of the switch, but the flare 61 which joins the sleeve 58 with the cup tends to throw mercury away from the cup in the event that excess voltage on the coil should lower the displacer 71 with such speed that a wave of mercury is thrown upwardly within the thimble 64 with sufficient force to momentarily compress the gas within the thimble. The flare 61 avoids a false make if such a situation should arise.

(h) Although a glass insert 73 is shown in conjunction with the magnetic sleeve 72, it is unnecessary to use a liner of this type to protect the magnetic sleeve from deterioration due to the effect of the arc at the electrodes, since the thimble 64 serves this function. The liner in such cases is used merely to give the displacer additional buoyancy.

The switch shown in Figs. 5-8 inclusive can be readily made into a slow make, slow break switch merely by proportioning the mercury fill, height of the electrodes, shape of the glass thimble, etc. so that the opening 66 is at all times below the outside mercury level. A switch so constructed very clearly illustrates the advantage which this type of construction has over switches in which the time delay element is carried by the displacer, particularly with respect to relatively small displacer oscillations produced by voltage changes in the coil, and when the mercury level on the inside of the time delay element is closely adjacent to the level at which it changes the condition of the electrical circuit through the switch. It also has the inherent advantage in that when the mercury level on the inside of the thimble is falling away from the intermittently immersed electrode, the heat created by the arc at the moment the circuit is broken instantaneously expands the gas in the thimble and accelerates the breaking of the circuit so that the arc is held down to a minimum. The thimble in a sense becomes an explosion chamber in which the expanding gas accelerates the movement of mercury away from the contact being broken, thereby extinguishing the arc.

In order to protect adjacent property from damage due to leaking mercury in the event that the switch should become broken, the switch envelope is preferably encased within a sealing jacket 80 made of a material known as Sealon. This jacket is applied to the envelope while in a wet condition, and as it dries, it shrinks radially, but not longitudinally, to tightly encase the envelope. The Sealon jacket is transparent so that the switch parts can be inspected through the jacket and it is strong and tough with great resistance to tearing.

Preferably a metal cap 81 is held in place by a suitable cement 82 over the tip 77 of the envelope so that the jacket 80 when shrunk into place will completely encase the envelope and seal the mercury within it, even though the glass envelope may become broken.

Switch having quick make and delayed break

The switch shown in Figs. 9-14 inclusive is a back contact switch characterized by the fact that it immediately closes the electrical circuit through the electrodes whenever the associated relay coil is de-energized and delays the opening of the circuit for a given period of time when the coil is energized. In addition to this, however, the switch has the unusual and important property or attribute that it will always give the desired time delay on the breaking of the circuit no matter what the recycling period for the relay coil may be.

The principles of this switch may also be incorporated in a front contact switch, as will readily be understood by reference to Figs. 5-8 inclusive, but as here shown, the switch comprises a switch envelope 85 having electrodes 86 and 87 sealed through the base in a manner very similar to the switch disclosed in Figs. 5-8 inclusive. The time delay element 88 is rigidly attached to both of the electrodes 86 and 87, the latter extending into the thimble 89 and terminating in an exposed end 90 surrounded by a refractory cup 91 containing a quantity of mercury. The thimble 89, as before, is preferably made of glass and has an opening 92 on the opposite side from the cup 91.

The top of the thimble 89 is equipped with a mercury check valve, generally designated 93, which allows gas to freely pass from the interior of the thimble to the exterior of the thimble but restricts the flow of gas in the opposite direction. The check valve comprises a porous seat 94 of coarse ceramic material (such as Alundum, grade RA 98) and an upwardly extending short tube 95 (preferably Alundum grades RA 360 or RA 84 according to the time delay desired) the tube 95 forming with the seat 94 a cup adapted to retain a small quantity of mercury 96 over the seat 94. The seat and the tube are both fused to the top of the glass thimble 89 and preferably the tube 95 is cut away, as best shown in Fig. 12.

The switch envelope contains a mercury fill 97 and a magnetically responsive displacer 98, the form of which is somewhat different from the displacer 71 of the front contact relay shown in Figs. 5-8 inclusive, because of the need of additional weight in the displacer for obtaining positive action of the switch. The opening 99 in the top of the displacer is of sufficient size so that it does not in any way modify the movement of either the displacer or the mercury within the envelope. As before, springs 75 and 76 are attached to the top and bottom of the displacer to cushion the movement of the displacer within the envelope.

When the coil associated with the switch is de-energized, the parts assume the position in which they are shown in Fig. 9, and it should be noted that the mercury level is such that the check valve cup 95 is assured of a filling of mercury. The notch 100 formed in the cup prevents any entrapment of gas in the cup which might hinder the cup in filling. In this position of the switch parts, the electrical circuit between the electrodes 86 and 87 is closed through the mercury fill 97.

When the displacer is raised by energization of the coil 21, the outside mercury level immediately falls to the position in which it is shown in Fig. 10, but the measured quantity of mercury within the mercury chamber in the thimble 89 (the same quantity 75 is always assured because the high mercury

level as shown in Fig. 9 is above the top of the mercury chamber in the thimble) is retarded in its downward movement due to the slow entry of gas through the walls of the tube 95 and the porous seat 94, as shown by the arrows in Fig. 12. In effect, the mercury valve is by-passed by the passage of gas through the walls of the tube and through the seat. The mercury level finally recedes until a mercury level is established with both the inside and outside mercury levels resting at the position indicated by the line 101, the contact, however, being broken at the instant when the mercury within the thimble falls below the edge 102 of the refractory cup 91 associated with the bared end 90 of the electrode 87.

Upon de-energizing the coil 21, the displacer raises the mercury level to the position in which it is shown in Fig. 9, and the mercury 96 in the check valve 93 readily passes the gas within the thimble through the coarse ceramic material constituting the seat 94 with the result that the circuit through the electrodes 86 and 87 is made substantially instantaneously upon release of the coil 21.

It is important to note at this point that the desired time delay on the breaking of the electrical circuit is always obtained no matter what the period of recycling for the relay may be. In other words, a minimum time delay period will always exist between the energization of the relay coil 21 and the opening of the circuit through the electrodes 86 and 87, although de-energization of the coil 21 before the minimum time delay period has expired will cause the time delay element to be reset for subsequent energization of the relay coil. This desirable result is achieved without any possibility of a false contact being made due to unexpected short cycling of the relay.

A slight modification of the mercury check valve arrangement is shown in Figs. 13 and 14 in which the time delay element consisting of a cylindrical plug 103 of suitable ceramic material is physically separated from the mercury valve. In this case, the seat 94 is the same as before, but the tube 104 which forms the cup for the mercury is made of molybdenum, or other suitable non-porous material. Molybdenum is preferred because it will seal with glass and because it permits the seat 94 to be fused with the tubing 50 by glass indicated at 105.

The action of the modified form of time delay element is substantially the same as before: Gas within the thimble can escape quickly through the coarse ceramic seat 94 and out through the mercury 96 in the cup without any appreciable impedance, but gas can only enter the thimble through the time delay element 103 which measures the minimum amount of time required for breaking of the circuit through the electrodes 86 and 87.

Throughout the specification and claims, the expression "low mercury level" is used to designate the level of the mercury when the displacer is in its raised position and the column of mercury within the time delay thimble is in equilibrium with the column of mercury on the outside of the thimble. By way of example, the mercury fill in Fig. 5 is shown at its "low mercury level" and in Fig. 10, the reference numeral 101 indicates the low mercury level. Similarly, the expression "high mercury level" throughout the specification and claims is used to designate the level of the mercury fill when the displacer is in its lowered position (see Figs. 6 and 9) and the 75

inside and outside mercury columns are at rest. The reference line 78 in Fig. 6 indicates the high mercury level for the switch there disclosed, and in Fig. 9, the mercury is shown at its high mercury level.

The plug 94 in the form of the invention shown in Figs. 9-14 inclusive may, if desired, be made of somewhat denser material, so that a certain time delay is effected on the making of the circuit through the electrodes as well as on the breaking of the circuit, the latter, of course, being accomplished by the still denser material constituting either the tubing 95 (Fig. 12) or the plug 103 (Fig. 14).

15 I claim:

1. In a mercury switch, a switch envelope, a mercury fill, a gas fill, spaced electrodes in the envelope, one of which projects upwardly through the mercury fill and is surrounded by an insulating sleeve to a point above the low mercury level, leaving an exposed end, a thimble telescoped over the exposed end and having its lower portion bonded to the sleeve, said thimble having a large opening adjacent to the bond for the free passage of mercury to and from the interior of the thimble, and a small opening adjacent to the top of the thimble for the restricted passage of gas between the interior and the exterior of the thimble in at least one direction.

20 2. In a mercury switch, a switch envelope, a mercury fill, a gas fill, spaced electrodes in the envelope, one of which projects upwardly through the mercury fill and is surrounded by an insulating sleeve to a point above the low mercury level, leaving an exposed end, a time delay thimble telescoped over the exposed end and having its lower portion bonded to the sleeve, said thimble having a large opening adjacent to the bond for the free passage of mercury to and from the interior of the thimble, and a small opening adjacent to the top of the thimble for the restricted passage of gas to and/or from the interior of the thimble, and means for having the second electrode assist in the support of the 25 thimble.

25 3. In a mercury switch, a switch envelope, a mercury fill, a gas fill, spaced electrodes in the envelope, one of which projects upwardly through the mercury fill and is surrounded by an insulating sleeve to a point above the low mercury level, leaving an exposed end, a time delay thimble telescoped over the exposed end and having its lower portion bonded to the sleeve, said thimble having a large opening adjacent to the bond for the free passage of mercury to and from the interior of the thimble, and a small opening adjacent to the top of the thimble for the restricted passage of gas to and from the interior of the thimble, and a refractory cup mounted 30 on the exposed end of said one electrode.

4. In a mercury switch, a switch envelope, a mercury fill, a gas fill, spaced electrodes in the envelope, one of which is adapted to be intermittently placed in electrical contact with the mercury fill, a thimble telescoped over the end of said one electrode, and rigidly supported in fixed position by attachment to both of said electrodes, and a porous plug constituting at least a portion of the wall of the thimble for restricting the flow of gas therethrough.

5. In a mercury switch, a switch envelope, a mercury fill, a gas fill, spaced electrodes in the envelope, one of which is adapted to be intermittently placed in electrical contact with the mercury fill, a thimble telescoped over the end

of said one electrode, and rigidly supported in fixed position by attachment to at least one of said electrodes, a porous plug constituting at least a portion of the wall of the thimble for restricting the flow of gas therethrough, and a mercury valve associated with said plug.

6. In a mercury switch, a switch envelope, a mercury fill, a gas fill, spaced electrodes in the envelope, one of which is adapted to be intermittently placed in electrical contact with the mercury fill, means for raising and lowering the mercury fill, and a time delay element supported by and rigidly attached to at least one of said spaced electrodes, said element comprising a restricted gas passage, and means for by-passing the restricted passage when the gas is moving in one direction.

7. In a mercury switch, a switch envelope, a mercury fill, a gas fill, spaced electrodes in the envelope, one of which is adapted to be intermittently placed in electrical contact with the mercury fill, means for raising and lowering the mercury fill, a time delay element associated with one of said electrodes for delaying the movement of mercury in one direction in the vicinity of said one electrode, said time delay element comprising a thimble telescoped over said one electrode and having an opening in a horizontal wall thereof, a ceramic cup in the opening having gas pervious side and bottom walls, and mercury in the cup restricting the flow of gas into the thimble to that which permeates the side walls of the cup.

8. In a mercury switch, a switch envelope, a mercury fill, a gas fill, spaced electrodes in the envelope, one of which is adapted to be intermittently placed in electrical contact with the mercury fill, means for raising and lowering the mercury fill, and a time delay element associated with one of said electrodes for delaying the movement of mercury in one direction in the vicinity of said one electrode, said time delay element comprising a thimble telescoped over said one electrode and having an opening in a horizontal wall thereof, a mercury cup in the opening having its bottom wall of material that is impervious to mercury, but which offers substantially no resistance to the passage of gas, positive means for filling the mercury cup for each cycle of switch operation, and means for slowly admitting gas to the thimble.

9. In a mercury switch, a switch envelope, a mercury fill, a gas fill, spaced electrodes in the envelope, one of which is adapted to be intermittently placed in electrical contact with the mercury fill, means for raising and lowering the mercury fill, and a time delay element associated with one of said electrodes for delaying the movement of mercury in one direction in the vicinity of said one electrode, said time delay element comprising a thimble telescoped over said one electrode and having an opening in a horizontal wall thereof, a mercury cup in the opening having gas pervious side and bottom walls, mercury in the cup restricting the flow of gas into the thimble to that which permeates the side walls of the cup, and means for filling the mercury cup upon each operation of the switch, said cup having a portion of its side wall of greater height than the remaining portion to facilitate the filling of the cup with mercury.

10. For use in a mercury switch of the class described, a switch blank comprising an envelope, spaced electrodes in the envelope extending longitudinally into the envelope, a glass thim-

ble fused to, supported by and rigidly attached to both of said electrodes, and a gas pervious member constituting at least a portion of the wall of the thimble.

5 11. In a mercury switch, a switch envelope, a mercury fill, a gas fill, spaced electrodes in the envelope, one of which projects upwardly through the mercury fill and is surrounded by an insulating sleeve to a point above the low mercury level, leaving an exposed end, a time delay thimble telescoped over the exposed end and having its lower portion bonded to the sleeve, said thimble having a large opening in one of its side walls adjacent to the bond for the free passage 10 of mercury to and from the interior of the thimble, and a small opening adjacent to the top of the thimble for the restricted passage of gas to and from the interior of the thimble, the exposed end of said one electrode being closely adjacent 15 to the side wall of the thimble opposite from that in which the mercury opening is provided.

12. In a mercury switch, a switch envelope, a mercury fill, a gas fill, spaced electrodes in the envelope, one of which projects upwardly through the mercury fill and is surrounded by an insulating sleeve to a point above the low mercury level, leaving an exposed end, a time delay thimble telescoped over the exposed end and having its lower portion bonded to the sleeve, said thimble having a large opening adjacent to the bond for the free passage of mercury to and from the interior of the thimble, and a small opening adjacent to the top of the thimble for the restricted passage of gas to and from the interior of the thimble, and a refractory cup mounted on the exposed end of said electrode and bonded to the insulation surrounding that electrode, the bond between the cup and the sleeve surrounding said one electrode being flared upwardly and 20 outwardly whereby mercury moving rapidly toward said one electrode is momentarily thrown away from the cup.

13. In a mercury switch, a glass envelope, a mercury fill, a gas fill, spaced electrodes sealed into one end of the envelope, a base fitted to the lower end of the envelope and held in place by a waxy substance, and a light transmitting thin-walled infrangible jacket shrunk over the switch envelope and at least a portion of the base for confining the mercury within the jacket in the event of breakage of the glass envelope.

14. In a mercury switch, a switch envelope, a mercury fill, a gas fill, spaced electrodes in the envelope, one of which projects upwardly through the mercury fill and is surrounded by an insulating sleeve to a point above the low mercury level, leaving an exposed end, a time delay thimble telescoped over the exposed end and having its lower portion bonded to the sleeve, said thimble having a large opening adjacent to the bond for the free passage of mercury to and from the interior of the thimble, and a small opening adjacent to the top of the thimble for the restricted passage of gas to and from the interior of the thimble, the opening for the mercury being substantially equal to or larger than the diameter of the thimble.

15. In a time delay mercury switch adapted to produce a relatively quick make and a slow break 70 of the circuit which it controls, the combination of a switch envelope, a mercury fill, a gas fill, spaced electrodes in the envelope, one of which is adapted to be intermittently placed in electrical contact with the mercury fill, a time delay 75 element associated with said one electrode and

comprising a thimble telescoped over that electrode and having a mercury valve in its upper portion, and means for raising and lowering the mercury fill to electrically connect the spaced electrodes through the mercury fill, the mercury fill and said means bearing such relationship to each other that the mercury valve is automatically filled each time that the mercury level is raised to electrically connect the spaced electrodes.

16. In a mercury switch, a switch envelope, a gas fill, a mercury fill, spaced electrodes in the envelope, one of which is adapted to be intermittently placed in electrical contact with the mercury fill, means for raising and lowering the mercury fill between specified high and low levels, and means for positively preventing mercury from falling away from said one electrode in less than a given time interval following the lowering of the mercury level, even though the mercury level is raised and lowered between said high and low levels in cycles which are shorter than the prescribed time interval, said latter means comprising a thimble telescoped over said one electrode and having a relatively large opening 20 for the free passage of mercury to and from the interior of the thimble, and a one way time delay element permitting gas to escape relatively freely from the thimble but restricting the flow of gas 25 into the thimble, said thimble bearing such relationship to the mercury fill and the associated switch parts that the high mercury level is at or above the top of the mercury chamber within the thimble whereby a measured quantity of mercury is always within the thimble subject to the 30 action of the restricted gas passage when the mercury level is shifted from its high position to its low position.

17. In a mercury switch, a switch envelope, a mercury fill, a gas fill, spaced electrodes in the envelope, one of which is adapted to be intermittently placed in electrical contact with the mercury fill, a thimble telescoped over the end of said one electrode, and rigidly supported in fixed position by attachment to at least one of 45 said electrodes, a porous plug constituting at least a portion of the wall of the thimble for restricting the flow of gas therethrough, and a mercury valve in another portion of the thimble permitting 50 gas to by-pass the plug when the gas is moving in one direction.

18. In a mercury switch, a switch envelope, a mercury fill, a gas fill, spaced electrodes in the envelope, one of which is adapted to be intermittently placed in electrical contact with the mercury fill, a thimble telescoped over the end of said one electrode and rigidly supported in fixed position by attachment at its base to at least one of said electrodes, and means including 55 a restricted gas passage for retarding the movement of mercury away from said one electrode, said thimble having a mercury chamber of relatively small area forming an explosion chamber to accelerate the breaking of the circuit at said one electrode at the instant when an arc is formed due to the breaking of the circuit.

19. In a mercury switch, a switch envelope, a mercury fill, a gas fill, spaced electrodes in the envelope, one of which is adapted to be intermittently placed in electrical contact with the mercury fill, a fixed time delay element associated with said one electrode, and means for attaching the element to both of said electrodes whereby it has rigid and stable support.

20. In a mercury switch, a switch envelope, a 75

- mercury fill, a gas fill, spaced electrodes in the envelope, one of which is adapted to be intermittently placed in electrical contact with the mercury fill, a fixed time delay element associated with and telescoped over said one electrode, a magnetically responsive displacer for shifting the mercury level, said displacer when in its lowered position being completely submerged within the mercury fill. 5
- 10 21. In a mercury switch, a glass envelope having a seal-off tip at its upper end, a mercury fill, a gas fill, spaced electrodes sealed into the lower end of the envelope, a base fitted to said lower end of the envelope and held in place by a waxy substance, a metal cap bonded with adhesive material over the seal-off tip, a light transmitting thin-walled infrangible jacket shrunk over the switch envelope and at least a portion of the base and the metal cap for confining the mercury within the jacket in the event of breakage of the glass envelope. 15
- 15 22. In a mercury switch relay, the combination of a vertical switch envelope, spaced electrodes sealed through the base of the envelope, 20 a coil telescoped over the envelope, a magnetic circuit associated with the coil and including a cylinder of magnetic material encasing the coil, a top for enclosing the upper end of the envelope, and a terminal box mounted below the coil for receiving the lower end of the envelope. 5
- 25 23. In a mercury switch, a glass envelope, a mercury fill, a gas fill, spaced electrodes sealed into the envelope, a fluid-tight jacket telescoped over the switch envelope and sealed above and below the envelope to completely incase it and to confine the mercury within the jacket in the event of breakage of the glass envelope. 10
24. In a mercury switch, a switch envelope, a mercury fill, a gas fill, spaced electrodes in the envelope, one of which is adapted to be intermittently placed in electrical contact with the mercury fill, means for raising and lowering the mercury fill, and a time delay element supported by and rigidly attached at its base to at least 20 one of said spaced electrodes, said element comprising a restricted gas passage, and means for by-passing the restricted passage when the gas is moving in one direction. 15

CARL H. LARSON. 25

CERTIFICATE OF CORRECTION.

Patent No. 2,224,873.

December 17, 1940.

CARL H. LARSON.

It is hereby certified that error appears in the printed specification of the above numbered patent requiring correction as follows: Page 2, second column, line 32, for "swtich" read --switch--; page 5, first column, lines 42 and 43, claim 2, for the words "to and/or from the interior of the thimble" read --between the interior and the exterior of the thimble in at least one direction--; and that the said Letters Patent should be read with this correction therein that the same may conform to the record of the case in the Patent Office.

Signed and sealed this 21st day of January, A. D. 1941.

Henry Van Arsdale,

(Seal)

Acting Commissioner of Patents.
